YIELDING REED

Carl D. Brown, Hopedale, Mass., assignor to
 Draper Corporation, Hopedale, Mass., a corporation of Maine

Application October 29, 1937, Serial No. 171,625

1 Claim. (Cl. 139—188)

The present invention pertains to yielding reed mechanisms for fly shuttle looms and more particularly to the fliter and fliter controlling devices of such mechanisms.

5 In looms of the type to which my invention applies, a reciprocating lay, including a lay beam, carries a reed which is rearwardly yieldable relative to the lay beam and which is yieldingly urged forwardly by spring-actuated bolts or rods. 10 These spring-actuated rods act on a fliter, so-called, which may support the lower reed rib. Adjusting means are usually provided, for adjusting the spring tension on the rods. The fliter must be freed from the action of these rods on 15 several occasions, such as whenever it is desired to test the freedom of the swinging movement of the reed or when the reed is to be removed from the loom for purposes of replenishing the warp supply.

20 Prior yielding reed mechanisms of the type above described were so constructed that the fliter could be freed from the action of the spring-actuated rods only by removing the actuating springs and the adjusting means therefor. Such 25 removal of the springs and adjusting means is inconvenient, time-consuming, and requires that the spring tension be readjusted before the loom is again put in operation.

I propose to provide a yielding reed mechanism 30 including the lay beam, a rearwardly yieldable fliter, and a spring-actuated rod for yieldingly urging the fliter forwardly, which fliter and rod shall be so constructed and arranged that the rod can be quickly and easily disengaged from 35 the fliter, and which shall not be subject to the above-mentioned disadvantages of prior constructions.

The foregoing and other objects of the invention are accomplished in the construction illustrated on the accompanying drawing, of which:

40 Fig. 1 is a view in rear elevation of part of a lay having the preferred embodiment of my invention applied thereto; and

Fig. 2 is a view in cross-section taken approximately on line 2—2 of Fig. 1.

45 The drawing shows part of a lay having my improved yielding reed mechanism, the other mechanisms of the loom (not shown) being of any suitable usual construction and forming no 50 part of the present invention. The lay construction shown on the drawing includes a lay beam 1 which is supported on lay swords such as the lay sword 2. The lay swords are of usual construction and are pivoted in the usual manner 55 so that the lay may reciprocate toward and from

the front of the loom, which is toward the right on Fig. 2. The lay carries a reed 3 for beating the filling into place, the reed being movable rearwardly relative to the lay beam.

5 In the particular embodiment shown on the drawing, the reed is fixed in a movable reed frame. This frame may include the usual hand rail 4 and a bar 5, commonly called a fliter. The hand rail and bottom bar are rigidly connected in spaced relation by end brackets such as the 10 bracket 6. The top reed rib 7 is received in a longitudinal groove in the under side of the hand rail 4, and the bottom reed rib 8 is received in a groove in the top of the fliter 5. The end brackets of the reed frame are pivoted on horizontal pivots, such as bolt 9, so that the reed frame and reed may swing forwardly and rearwardly relative to the lay beam. Forward movement of the reed is limited by adjustable stop screws 10 which are engaged by the fliter when 20 the reed is forward.

A bolt 11 and spring 12 comprises part of means for holding the reed against rearward movement during the time the lay is back and the shuttle is in flight. Such means is not active when the 25 lay is forward and it is not of the present invention. For a complete disclosure of the same, reference may be had to patent to E. C. Nichols, No. 2,087,859, granted July 20, 1937.

The present invention provides a novel means 30 for yieldingly resisting rearward movement of the reed frame, the preferred embodiment of which includes a series of rods and springs. The drawing shows only one such rod 13 and spring 14, the other rods and springs of the series being 35 spaced along the lay and being of exactly the same construction as those shown. The rod 13 shown extends forwardly and rearwardly of the loom below the fliter 5 and is supported by the lay beam 1 for both rotating and axial sliding 40 movement. To this end, the rod 13 may extend through a horizontal opening 15 in the lay beam which opening forms a bearing for the rod.

The rearward end of the rod 13 has a lateral projection 16 which engages behind the fliter 5. 45 The spring 14 is arranged to yieldingly urge the rod 13 forwardly, so that the spring and rod yieldingly resist rearward movement of the fliter and reed. As shown, the spring 14 is a helical coiled spring which is positioned on the forward end of 50 the rod and is compressed between the lay beam and adjusting nuts 17 which are threaded onto the rod. It will be apparent that by adjusting the nuts 17 the strength of the resistance to rearward movement of the fliter may be varied, to 55

adapt the mechanism to different weaving conditions.

The rod 13 is rotatable in its bearing 15 but is normally held against rotation, to hold the 5 projection 16 in engagement with the filter. In accordance with the present invention, such holding means is manually releasable, to permit the rod to be manually rotated whenever it is desired to free the filter from the action of the spring 10 14. In the embodiment shown, the projection 16 is formed by bending the rearward end of the rod 13 upwardly, and the aforesaid holding means is formed by bending the projection forwardly and inserting the forwardly extending end 18 into a 15 hole 19 which extends forwardly from the back of the filter.

During the normal operation of the loom, the end 18 will be seated in the hole 19 as shown, and the projection 16 is thereby held in engagement 20 with the filter. However, with this construction the reed and filter may be freed from the action of the spring 14 merely by pushing or sliding the

rod 13 rearwardly, to withdraw the end 18 from the hole 19, and then rotating the rod. This disengagement of the projection 16 from the filter is effected quickly and easily and without disturbing the adjustment of the nuts 17. 5

Having fully disclosed the preferred embodiment of my invention, I claim:

In a yielding reed mechanism for looms, the combination of a lay beam and rearwardly yieldable filter, with manually releasable means for 10 yieldingly resisting rearward movement of said filter, said means comprising a rod extending forwardly and rearwardly below said filter, the rearward end of said rod being bent upwardly and then forwardly and inserted into a hole extending 15 forwardly from the back of said filter, said rod being supported for rearward sliding movement to withdraw said end from said hole and being rotatable out of engagement with said filter, and a coiled spring on the forward end of said rod 20 for yieldingly urging the rod forwardly.

CARL D. BROWN.
